UNITED STATES PATENT OFFICE.

JOHN LEWIN, OF BERLIN-HALENSEE, GERMANY.

AUTOMATIC LIQUID STARTER FOR ALTERNATING AND THREE-PHASE CURRENT MOTORS.

Application filed June 5, 1922. Serial No. 565,950.

To all whom it may concern:

Be it known that I, JOHN LEWIN, a citizen of the Republic of Germany, residing at Berlin-Halensee, Germany, have invented 5 certain new and useful Improvements in Automatic Liquid Starters for Alternating and Three-Phase Current Motors; and I do hereby declare the following to be a full, clear, and exact description of the invention.

For starting alternating and three-phase current motors it has been suggested to effect a diminishing of the resistances within the armature winding, automatically, by 15 forming the said resistances by a conducting liquid, which latter under the influence of centrifugal force is distributed within a casing attached to the shaft of the motor in such a manner, that the effective cross-section of the liquid is increased, while the resistances are gradually diminished. The insulated electrodes electrically connected with the windings of the armatures are of 20 annular shape but rigidly secured within 25 the casing.

In contradistinction to this arrangement, the electrodes of the present centrifugal liquid starter are constructed as swinging segments of a concentric ring in such a manner, that not only the effective cross-section of the liquid layer is increased on account of the action of the centrifugal force, but also the distance of the electrodes from the walls of the casing will be diminished gradually. The liquid resistances connected to the armature windings are thus effectively diminished to a far greater extent than is possible with the annular fixed electrodes.

40 The swinging electrodes are advantageously made of flexible material so that they will be capable of better clinging to the walls of the casing during rotation. Besides, the electrodes may be provided at 45 certain points of their surfaces facing the walls of the said casing, with insulating material, so that in this instance a contact of the electrodes with the metal walls of the casing is avoided.

50 In the drawings

Fig. 1 is a starter in cross-section of a starter at rest, perpendicularly to the axis of rotation of the casing.

Fig. 2 is a cross-section thereof parallel 55 to the axis of rotation of the casing.

Figs. 3 and 4 show the starter during rotation.

Fig. 5 shows the final position of the electrodes.

Figs. 6 and 7 illustrate the connection of 60 the starter with the armature winding.

On the shaft W of the motor (Fig. 2) is secured the casing A, containing the electrodes B and B¹ pivoted on pins S and S¹ respectively. The pins S and S¹ and likewise the electrodes B and B¹ electrically connected with said pins, are insulated from the casing A and connected with the armature windings E and E¹ (Fig. 6), while the casing A is connected to the common 70 point of connection of the armature winding by means of the shaft W. This arrangement will be suitable for a rotor wound for two phases.

The electrodes are caused by springs F 75 and F¹ to engage insulated stop pins P and P¹ respectively, so that the former will only be able to swing outwardly under the action of centrifugal force when the speed of rotation increases (Figs. 3 and 4). Part of 80

the casing A is filled with a conducting liquid such as for instance, soda-water, which will remain at the bottom part thereof while the device is at rest. When the motor is started the effective cross-section 85 of the liquid formed at first by the liquid X is too small for the armature current, but as soon as the casing A is rotated, the liquid X is carried along so that the immersed surface of the electrodes B and B¹ gradually 90 increases, that is the resistance diminishes, until the liquid according to Figs. 3 and 4 is caused to form an annular layer, into which the electrodes B and B¹ are totally

immersed. The quantity of the liquid must 95 be adapted in accordance with the respective distance of the electrodes from the inner walls of the said casing. At a further increase of the speed of rotation the electrodes B and B¹ will swing outwardly and 100 approach the wall of the casing, thus further diminishing the resistance. If the motor ultimately has reached its proper number of revolutions, the electrodes will come near the wall of the casing A (Fig. 105

5) to an extent equal to the thickness of the insulating members J and J¹ attached to the electrodes, whereby the tension of the springs F and F¹ is overcome. The thickness of the layer of liquid between the elec- 110

trodes B and B¹ and the walls of the casing A is so small that practically through said layer of liquid a short-circuiting of the rotor-windings is effected, without running the danger of the electrodes burning fast on the walls of the casing.

Fig. 7 shows diagrammatically the armature starter of a rotor wound for three-phases.

10 I claim:

1. An automatic liquid starter for alternating and three-phase current motors comprising a casing rotatable with the shaft of the motor and partially filled with a conducting liquid forming resistances included in the winding of the armature, and segmental electrodes in the casing arranged to swing outwardly under the action of cen-

trifugal force and approach the walls of said casing.

2. An automatic liquid starter for alternating and three-phase current motors comprising a casing rotatable with the shaft of the motor and partially filled with a conducting liquid forming resistances included in the windings of the armature, flexible segmental electrodes in the casing arranged to swing outwardly under the action of centrifugal force, and insulating members between the electrodes and the casing.

In testimony that I claim the foregoing as my invention, I have signed my name.

JOHN LEWIN.
